UNITED STATES PATENT OFFICE.

JOHN S. DAVIS, OF TOLEDO, OHIO, ASSIGNOR TO THE TOLEDO MOWER
AND REAPER COMPANY, OF SAME PLACE.

BAND-SECURING MECHANISM FOR GRAIN-BINDERS.

SPECIFICATION forming part of Letters Patent No. 319,963, dated June 16, 1885.

Application filed April 5, 1884. (No model.)

To all whom it may concern

Be it known that I, JOHN S. DAVIS, of Toledo, in the county of Lucas and State of Ohio, have invented certain new and useful Improvements in Band-Securing Mechanism of 5 Grain Binders, of which the following is a specification.

My invention chiefly relates to improvements in that class of grain-binding mechanism for clamping, knotting, and cutting the binding material in which provision is made for supplying the binding material to a knotter, during the formation of the loop of the knot, from the band ends, instead of from or mainly 15 from the banding portion or length of the binding material which encircles a bundle and is included in the loop formed by crossing or bringing together at or near the knotter that portion of the binding material next the end 20 which is clamped and that portion next the end passing to the binder-arm.

Types of the class of mechanism to which my present invention relates are shown and described in United States Letters Patent for 25 other inventions of mine, granted June 5, 1883, No. 279,082, July 31, 1883, No. 282,445, and July 8, 1884, No. 301,808.

Instead of employing, in connection with co-operating devices, a vibrating knotter, as 30 shown in the referred-to patents of June 5, 1883, and July 31, 1883, or an oscillating cord-holder, by the turning and reciprocating member of which cord is taken up at the ends of the bands and supplied to the knotter, as 35 shown in the above-mentioned Patent No. 301,808, I now employ a non-turning cord-holder, the movable member of which has imparted to it a movement of reciprocation only, and is provided with a loop-retainer by means 40 of which cord is taken up at the ends of the bands to be given out during the formation of the knots.

In accordance with my present improvements, I employ various features described or 45 referred to in the before-mentioned patents, while simplifying the construction and lessening the cost of the mechanism now used as compared with that heretofore employed.

The accompanying drawings, which suffi-

ciently represent a suitable application of my 50 improvements, show only those features illustration of which, aided by reference to the before-mentioned patents if necessary, is thought to be needed to convey a proper understanding of the improvements herein 55 claimed. Some of these improvements may, however, be used without the others, or be employed in connection with mechanism differing in some respects from that shown and hereinafter particularly referred to. 60

Figure 1 is a plan view of the entire band-securing mechanism, the cover of the knotter box or easing for this mechanism being removed and the parts represented as in their normal or stationary positions. Fig. 2 is a 65 plan view showing a portion of the knotter-box without its cover, and a portion of the binder-arm with some parts of the mechanism omitted, and the movable member of the cord-holder in section on the line 2 2 70 of Fig. 9, the parts being represented as in the positions they are caused to assume at about the time the movable member of the cord-holder is to be projected and when the strain exerted by the knotter on the band 75 end has disengaged it from the loop-retainer of the movable member of the cord-holder. Fig. 3 is a plan view of a portion of the cover of the knotter-box. Fig. 4 is a view partly in side elevation and partly in section on the 80 lines 4 4 of Figs. 1 and 3, representing a device by the actuation of which the cord is adjusted in proper position to be engaged by the knotter. Fig. 5 is a view partly in side elevation and partly in section on the line 5 5 of 85 Fig. 1, the knotter being omitted. Fig. 6 is an end elevation, the binder-arm being partly shown, and the parts represented as in the positions they are caused to assume when a knot is nearly completed and the binder-arm about 90 to commence its upward movement. Fig. 7 is a view partly in elevation and partly in section on the line 7 7 of Fig. 2, showing a lever connected with and serving to actuate the cord-adjuster. Fig. 8 is a bottom view of the 95 movable member of the cord-holder, a portion of a band end being represented in dotted lines as passing about the loop-retainer, and in full

lines as having been drawn from the loop-retainer preparatory to being released by the clamp. Fig. 9 is a side elevation of the movable member of the cord-holder, a portion of the band end being represented by dotted lines as passing about the loop-retainer, and in full lines as having been drawn from the loop-retainer. Fig. 10 is a view partly in elevation and partly in section on the line 10-10 of Fig. 9. Figs. 11 and 12 are views in elevation of opposite sides of the movable member of the cord-clamp, its shank being broken away and the band end omitted.

A knotter, A, preferably in all respects such as that set forth in the before-mentioned Patent No. 301,808, and the same, except that it does not vibrate and does not have a jointed shaft, as that shown and described in the above-specified Patents Nos. 279,082 and 282,445, has its shaft B mounted to rotate in suitable bearings, *a b*, the shaft being provided with the actuating pinion at its inner end, and turning in opposite directions backward and forward, so as to cause the knotter to first engage the cord presented to it by the binder-arm C as it turns backward, and then form the loop and knot as it turns in the other direction, or forward, as heretofore.

The knotter-shaft B is provided, as before, (see my aforesaid Patent No. 301,808,) with a roller-carrying tappet-arm, D, the tappet-roller *d*, acting upon a lug which projects upwardly from the end of one arm of an elbow-lever, E, the opposite arm of which connects, by means of a slot at its end, with a downwardly-projecting lug of a sleeve, *f*, having a screw-connection with a reciprocating non-turning cord-holder shaft, F. The elbow-lever is mounted to vibrate about a vertical pivot, *e*, secured to the bottom of the knotter-box G, and the end of this lever which is acted upon by the tappet-arm vibrates close to the bottom of the knotter-box. By these means it will be seen that the reciprocating holder-shaft is actuated, as before, to project the movable member of the cord-holder, to be further on described.

In order that the cord-holder shaft at its inner end may be located sufficiently far from the pivot *e* of the elbow-lever E to admit of the action of the lever upon the shaft throughout a proper extent of the sweep or throw of the lever without cramping or binding the parts, and yet not interfere with the location of the knotter and cord-holder close to each other, the holder-shaft is inclined instead of being parallel to the knotter-shaft, the distance between the two shafts being greatest at their inner ends.

The holder-shaft F is supported so as to be capable of reciprocating in the direction of its length in suitable bearings, H and *h*, the bearing *h* being at the inner end of the knotter-box, and the outer bearing, H, formed with a bracket secured to the bottom of the knotter-box.

A spring, *g*, coiled about the holder-shaft, bears at its outer end against the bearing H

and at its inner end against a nut, I, adjustably secured to the shaft by means of the threaded portion *i* thereof. The spring acts upon the holder-shaft in opposition to the action of the elbow-lever E, and serves to slide the shaft inward after its outward movement by the lever, as will readily be understood.

The movable member J of the cord-holder is connected by means of its shank *j* with the outer end of the shaft F, close to the bearing H. To permit of ready adjustment of parts and facilitate repairs, the shank *j* is detachably connected with the holder-shaft by means of a screw or bolt, *k*, as shown. The shank of the cord-holder reciprocates in a guideway or open bearing, K, at the outer end of the knotter-box. As in this instance shown, the cord-holder shank is rectangular in cross-section, and fits sufficiently snugly in its guideway-bearing to prevent any turning movement of the reciprocating member of the cord-holder and its shaft. Obviously turning movement of the holder-shaft and member J of the holder might be prevented in other and equivalent way, as by spline-and-groove connection between the shaft and one or both of its bearings.

The reciprocating non-turning member of the cord-holder, in addition to being so constructed as to clamp and cut the cord in connection with a fixed member of the holder and a fixed knife, which are soon to be described, is made to engage and temporarily retain a portion of the cord next the clamped end of each band, the cord so retained being given up under tension to the knotter during the formation of a knot and preparatory to the release of the clamped end of a band and the completion of the knot. The details of construction of the two members of the holder are as in this instance shown, as next to be described.

The fixed member L of the cord-holder is formed of some suitable, durable, and yielding or compressible material, preferably leather, secured in a cavity or niche in the outer end of the knotter-box, and provided with a recess, *l*, in its face. The leather is detachably clamped in place by means of a plate, M, the edge of which forms the fixed knife, and a bolt and nut, *m*, as will readily be understood from inspection of the drawings. The fixed knife-plate bears against the inner side of the holder-leather L—that side next the knotter; and between the opposite or outer side of the leather and the face recess *l* thereof it forms a bearing, *n*, against which a loop-retainer, N, of the reciprocating member of the cord-holder presses, as further on to be made apparent.

The shank *j* of the cord-holder reciprocates above the fixed member of the holder, and the inner end of a downwardly-projecting rib or lip, *o*, of the reciprocating member of the holder enters the recess *l* to clamp the cord.

A movable knife-section is formed by the inner edge of a downward projection or

shoulder, *p*, of a plate, *P*, riveted or otherwise secured to the inner side of the holder-shank.

Beneath the level of the holder-shank, and between the clamping-lip *o* and knife-plate shoulder *p*, there is a recess or opening, *O*, in the reciprocating member of the holder. This opening extends to the bottom and end of the member *J*, and allows of the ready escape of detached particles of cord, such as may fret off from the band ends, and thus prevent clogging of parts.

The loop-retainer *N* is formed by a laterally and vertically extending lug at the outer side of the reciprocating member of the cord-holder—that side most remote from the knife. As shown, the loop-retainer extends from the top of the cord-holder member *J* downwardly, terminating at its lower end beneath the level of the holder-shank and above the level of the lower surface of the lip *o*. At its lower end the loop-retainer is curved inwardly, or toward the fixed member of the cord-holder, as at *q*, and its lower edge is rounded off or inclined toward the lip *o*, as at *r*. The curved end *q* of the loop-retainer extends inwardly, so as to press against the bearing *n*, provided by the fixed member of the holder, when the cord is clamped in the recess *l* by the lip *o*, but with only a slight degree of pressure, or at least a pressure less than that of the lip *o* against the cord in the recess *l*, the lip *o* extending farther inward than the end of the loop-retainer, and consequently bearing with sufficient force against the fixed member to properly clamp the cord.

The knife plate shoulder *p* and the lip *o* are provided with notches *s t* in their under surfaces to be engaged by the cord and prevent accidental displacement of the band ends.

From the above description, with the aid, if needed, of the before-mentioned patents and application, the operation of the devices so far explained will be understood to be as follows, assuming that proper binding mechanism and mechanism for starting the binding mechanism in action upon the accumulation of a gavel are provided: The end of the cord having been clamped after being first passed about the loop-retainer, (see Figs. 1 and 5,) cord will be passed from the holder to the knotter when by the rotation of the knotter it reaches a point in its operation when cord is to be taken from the holder to form the loop of knot, the pull by the knotter on the clamped band end drawing the cord down and around the edge of the loop-retainer and along between the curved lower end and the bearing *n*, against which it is pressed and yieldingly held. The loop of cord extending from the lip *o* and recess *l* to and around the retainer *N*, being held with sufficiently slight pressure, is, when properly strained, allowed to slip down over the end of the retainer and pass along in between the bearing *n* and the adjacent surface of the retainer *N*, and to pass to the knotter by the give or compression of the bearing against

which the retainer works, as well as by a slight outward movement of the reciprocating cord-holder member against the force of its spring 70 in event of such movement being necessary. The cord having been pulled over the end of the loop-retainer, and along between the edge of the retainer and the bearing *n*, and the band end having passed from the position in which it is shown in Figs. 1 and 5, and by dotted lines in Figs. 8 and 9, to that in which it is represented in Fig. 2, and by full lines in Figs. 8 and 9, the projection of the reciprocating member of the holder by the action of 80 the knotter-shaft tappet and the elbow-lever on the cord-holder shaft next releases the band end, and the knot is completed and cast off in manner needing no description here. The reciprocating holder-section as moved outward crosses above and hooks over the cord next, the binder-arm, and the inward movement of this holder-section by its spring, when allowed to act by the release of the elbow-lever by the tappet, cuts and clamps the cord. Next, 90 the binder-arm is moved back to its inoperative position, drawing the cord about the loop-retainer and engaging it with the notches *s t*, preparatory to a repetition of the above-described steps. 95

In order to insure engagement of the cord by the knotter, by guarding against the possibility of the cord being accidentally pressed downward by the grain or otherwise out of the reach of the knotter, I provide means, such as soon to be described, by which the cord is pressed upward and supported in proper position to be acted upon by the knotter.

A guideway-slot, *Q*, for the cord, (shown as formed in the inner wall or side of the cover 105 *R* of the knotter-box, extending from the lower edge to the top of said side, having a wide or flaring lower end and inclined outward slightly,) communicates with a cord-guiding slot, *S*, formed in the top of the cover, and made sufficiently wide at the proper point to allow of the ready exit of the knots formed in the bands. An endwise reciprocating cord-adjuster, *T*, acts upon the cord after it has been presented beneath the knotter by the descent of the binder-arm, and presses the cord upward along the upwardly-extending guideway *Q*, thus causing the cord to bear against the knotter and to slightly incline outward therefrom so as to greatly facilitate engagement of the knotter-jaws with the cord, the knotter, as heretofore, being first turned downward to cause its jaws to pass beneath the cord, and then turned in the opposite direction to hook and engage the cord and form the knot. 110 115 120 125

The details of construction of the cord-adjuster, its connecting mechanism, and the manner of actuating it, as in this instance shown, are as follows: The cord-adjuster is located close to the inner wall or side of the knotter-box, is supported and guided at its outer end in a slot, *U*, in the end wall of the knotter-box, has a nose, *V*, inclined or sloping upward from its extreme outer end or rounded point to a 130

shoulder, v , and is formed with an incline, w , on its lower edge near its outer end. This incline w works in contact with the rounded bottom wall, u , of the guideway-slot U, and 5 serves to elevate the nose of the cord-adjuster when it is projected. The cord-adjuster is recessed or cut away at top from the shoulder v to a shoulder, W, at its inner end. A guide-stud, v' , projecting inwardly from the side of 10 the knotter-box, crosses above and close to the cord-adjuster, between its shoulders v and W. The cord-adjuster is perforated at its inner end, and has jointed connection with a horizontally-vibrating lever, W' , the rounded outer 15 end, w' , of which passes through the perforation in the cord-adjuster sufficiently loosely to allow of proper play of the parts, and projects into a recess in the side of the knotter-box. The lever W' is pivotally attached near its 20 heel end to the bottom of the knotter-box by a pivot-bolt passing through the perforated boss or hub x of the lever. At the heel end of the lever W' there is provided a perforated slotted lug, x' , by means of which and a suitable pivot the lever has jointed connection with 25 the inner end of an endwise reciprocating rounded bar or push-rod, X, which is supported at its outer end in a bearing formed by a perforation, X' , in the end wall of the knotter- 30 box. A spring, Y, is coiled between its ends about a stud, Y' , suitably secured to the bottom of the knotter-box, and projects at its ends in opposite directions, one end bearing against the heel of the lever W' , and the other press- 35 ing against a stop or buffer, y , preferably of rubber, secured by a bolt to the bottom of the knotter-box near its inner side. A notched side lug, y' , serves to insure proper contact of the spring with the lever, the spring engaging 40 the notch of the lug. The outer end of the push-rod is provided with an incline, z . At the point or nose of the binder-arm it is provided with the rounded inner surface or incline, Z. A support and guideway, Z', for the 45 binder-arm, at and near its nose, is shown as formed by a bracket-arm secured by screws to the under surface of the bottom of the knotter-box and bent upward at its outer end, the space between the inner surface of the up- 50 wardly-extending end z' of the guideway support and the end of the knotter-box being such as to admit the binder-arm freely, while preventing any lateral or outward movement thereof.

55 From the above description it will be seen that the cord-adjuster is operated in the following way: Upon the descent of the binder-arm its nose enters the guideway-support, bearing at its outer side against the rounded inner surface of the end z' of the support, while the incline Z acts against the inclined end of the push-rod, thrusting this rod inward, moving the lever with which it is connected, and projecting the cord-adjuster into the position in 60 which it is represented in Fig. 2, and by dotted lines in Figs. 4 and 5, and in this way di-

recting the cord from the position it is first caused to assume by the binder-arm (see Fig. 4) to that in which it is represented by dotted lines in Figs. 1 and 4, so as to be readily engaged by the knotter. When the binder-arm moves upward and leaves the push-rod free, it is thrust outward by the spring Y to the limit of its movement in this direction, and the cord-adjuster is retracted. The suddenly-imparted 75 inward movement of the push-rod and cord-adjuster is gradually arrested by contact of their lever with the yielding stop y , and the parts then assume their normal positions under the controlling influence of their actuating-spring, the push-rod projecting into the path of the binder-arm, so that the above-described steps are repeated upon the next actuation of the binder-arm.

I claim as of my own invention—

1. A cord-holder having a reciprocating non-turning member provided with a loop-retainer about which the cord passes and is yieldingly held next the clamped end of the band, substantially as and for the purpose hereinbefore set forth.

2. The combination of a knotter, the reciprocating non-turning member of the cord-holder provided with a loop-retainer for detaining cord and giving it up to the knotter, 91 and the fixed member of the cord-holder provided with a bearing against which the cord is yieldingly held by the loop-retainer, substantially as and for the purpose hereinbefore set forth.

3. The combination of a knotter and a cord-holder having a reciprocating non-turning member provided with a loop-retainer about which the cord passes and is yieldingly held, and from which the cord is pulled under tension by the knotter to form the loops of the knots, substantially as hereinbefore set forth.

4. The combination, substantially as hereinbefore set forth, of the rotary knotter, the fixed member of the cord-holder, the movable member of the cord-holder provided with the loop-retainer acting against the yielding bearing provided by the fixed member of the cord-holder, and the binder-arm, for the purpose described.

5. The fixed member of the cord-holder, provided with the face-recess and the yielding bearing for the loop-retainer, substantially as and for the purpose hereinbefore set forth.

6. The combination of the knotter-box provided with the end cavity or niche, the compressible material therein, and the fixed knife-plate by the securing devices of which said material is clamped in place, substantially as and for the purpose hereinbefore set forth.

7. The member J of the cord-holder, provided with the clamping-lip, and having the knife at its inner side and the loop-retainer at its outer side, substantially as and for the purpose hereinbefore set forth.

8. The member J of the cord-holder, provided with the loop-retainer having the in-

wardly curved lower end and the rounded edge, substantially as and for the purpose hereinbefore set forth.

9. The combination of the fixed member of the cord-holder and the member J thereof having the loop-retainer curved inwardly at its lower end and the lip projecting beneath and inside of the loop-retainer, substantially as and for the purpose hereinbefore set forth.

10. The combination of the knife having the notch in its lower surface, and the reciprocating member of the cord-holder having the loop-retainer and provided with the lip projecting beneath and inside of the loop-retainer and having the notch in its under surface, substantially as and for the purpose hereinbefore set forth.

11. The combination of the fixed member of the cord-holder, the fixed knife, the reciprocating member of the cord-holder having the knife, the loop-retainer, and the downwardly-projecting clamping-lip, the cord-holder shank above the fixed member of the holder, and means for projecting and retracting the reciprocating member of the holder, substantially as and for the purpose hereinbefore set forth.

12. The combination of the knotter, the binder-arm, and the endwise reciprocating cord-adjuster projected by means of connecting mechanism actuated by the binder-arm, substantially as and for the purpose hereinbefore set forth.

13. The combination, substantially as hereinbefore set forth, of the knotter, the binder-arm, the endwise reciprocating cord-adjuster, the connecting mechanism actuated by the binder-arm to project the cord-adjuster, and the spring actuating said mechanism for retracting the cord-adjuster.

14. The combination of the knotter-box, the reciprocating cord-adjuster projecting through the slot in the knotter-box and provided with the inclined nose and the incline on its lower edge, substantially as and for the purpose hereinbefore set forth.

15. The combination of the knotter-box cover having the cord-guideway Q, and the reciprocating cord-adjuster having the inclined nose projecting through a slot in the knotter-box and provided with the incline on its lower edge, substantially as and for the purpose hereinbefore set forth.

16. The combination of the knotter-box

cover, the reciprocating cord-adjuster having the inclined nose projecting through a slot in 55 the knotter-box and provided with the incline on its lower edge, and the guide-stud, substantially as and for the purpose set forth.

17. The combination of the knotter-box cover having the cord-guideway Q, the reciprocating cord-adjuster having the inclined nose projecting through a slot in the knotter-box and provided with the incline on its lower edge, and the guide-stud, substantially as and for the purpose hereinbefore set forth. 65

18. The combination of the endwise-reciprocating cord-adjuster, the lever having jointed connection therewith, the spring acting on the lever to retract the cord-adjuster, and the push-rod jointed to the lever, and by the actuation of which the cord-adjuster is projected, substantially as and for the purpose hereinbefore set forth. 70

19. The combination of the endwise-reciprocating cord-adjuster, its spring-actuated lever, and the endwise-reciprocating push-rod jointed to the lever and projecting into the path of the binder-arm, substantially as and for the purpose hereinbefore set forth. 75

20. The combination of the binder-arm 80 having the inclined nose, the cord-adjuster, and the endwise-reciprocating push-rod of its connecting mechanism actuated by the binder-arm, substantially as hereinbefore set forth.

21. The combination of the binder-arm, the 85 bracket-arm secured to the knotter-box and forming the guideway for the ends of the binder-arm, and the push-rod of the cord-adjuster mechanism, substantially as and for the purpose hereinbefore set forth. 90

22. The combination of the reciprocating cord-adjuster, the lever of its connecting mechanism, the spring supported between its ends projecting in opposite directions and acting at one end on said lever, and the buffer 95 against which the opposite end of the spring bears and by which the inward movement of the cord-adjuster and its mechanism is checked, substantially as and for the purpose hereinbefore set forth. 100

In testimony whereof I have hereunto subscribed my name.

JOHN S. DAVIS.
